DESIGN FOR AN AUTOMOBILE TRANSPORT

Irving H. Judd, Dearborn, Mich., assignor to Whitehead & Kales Company, River Rouge,
Mich., a corporation of Michigan

Application April 27, 1936, Serial No. 62,341

Term of patent 14 years

To all whom it may concern:

Be it known that I, Irving H. Judd, a citizen of the United States of America, residing at Dearborn, Wayne County, Michigan, have invented a certain new, original, and ornamental Design for an Automobile Transport, of which the following is a specification, reference being had therein to the accompanying drawing forming a part thereof, wherein:

I claim:

The ornamental design for an automobile transport substantially as shown.

IRVING H. JUDD.
